UNITED STATES PATENT OFFICE.

SYLVANUS F. BOWSER, OF FORT WAYNE, INDIANA.

MASSAGE APPARATUS.

No. 863,143.

Specification of Letters Patent.

Patented Aug. 13, 1907.

Application filed August 31, 1904. Serial No. 222,783.

To all whom it may concern:

Be it known that I, SYLVANUS F. BOWSER, a citizen of the United States, residing at Fort Wayne, in the county of Allen and State of Indiana, have invented 5 a new and useful Massage Apparatus, of which the following is a specification.

This invention relates to massage apparatus.

The object of the invention is to provide a massage apparatus which is exceedingly simple in construction, inexpensive to manufacture, and efficient in 10 operation.

A further object of the invention is to provide an apparatus of the nature referred to which may be used manually to massage any part of the body, or which 15 may be secured in a doorway, or in any other convenient place, and at adjustable heights, and against which the body, or any desired part thereof, may be rubbed.

Other objects of the invention will appear more fully 20 hereinafter.

The invention consists substantially in the construction, combination, location and relative arrangement of parts, all as will be more fully hereinafter set forth, as shown in the accompanying drawings, and finally 25 pointed out in the appended claims.

Referring to the accompanying drawings, and to the various views and reference signs appearing thereon,—

Figure 1 is a view in front elevation of one form of 30 massage apparatus embodying the principles of my invention, and showing the application of the same to a doorway. Fig. 2 is a front elevation of the form of massage apparatus shown in Fig. 1, one of the massage rollers being shown in section. Fig. 3 is a view 35 in longitudinal central section on the line 3, 3, Fig. 2, looking in the direction of the arrows. Fig. 4 is a view in transverse section on the line 4, 4, Fig. 3, looking in the direction of the arrows. Fig. 5 is a view in rear elevation, parts broken off, showing means 40 for clamping the device in a doorway or other convenient place.

The same part is designated by the same reference sign wherever it occurs throughout the several views.

The virtue of superficial friction such as is derived 45 from massage in the treatment of certain ailments, such as rheumatism, sciatica, lumbago, and the like, as well as obesity and other ailments, has become well established. The methods of treatment as commonly carried out are expensive, and frequently it is inconvenient 50 for the patient to give the necessary time for the treatments, or to maintain anything like regularity in observing appointments for a course of treatments, especially during business hours, and moreover, where the treatments are given by hand manipulations there 55 is a failure, frequently, to attain the desired degree of friction or pressure, or to reach the desired spots. It

is among the special purposes of my present invention to provide a massage apparatus which is simple and efficient, and capable of being manipulated by the individual desiring or requiring its use, which may 60 be employed morning or night upon rising or before retiring, which is handy and convenient for use, which may be readily applied to any desired part of the body and with any desired degree of pressure, which may be applied either in the form of a hand 65 device or in the form of a stationary device capable of ready and easy adjustment for height, or otherwise, and against which the body, or any desired part thereof, may be rubbed, with a suitable degree of pressure, and wherein the parts composing the rub- 70 bing surface are in themselves inelastic or non-yielding.

In the several figures of the drawing there are illustrated a number of particular or specific forms of the generic invention, and these specific forms will be hereinafter described in order that those skilled in 75 the art may know what I now regard as the best forms in which the invention may be carried out, although the invention in its generic sense is, of course, not limited to these specific forms, but in scope corresponds with the expression of it set forth in the claims, 80 and I therefore do not desire to be limited or restricted to any specific form of construction used to illustrate in the subjoined specification and accompanying drawings. In the present application, however, while claiming broadly all the various forms of my invention, I have claimed specifically only one of them; and in my companion applications filed of even date herewith, and bearing Serial Nos. 222,784 and 222,785, I have claimed specifically certain of the forms herein 85 shown and described. 90

Referring to Figs. 2, 3, 4 and 5 of the drawings, the rollers A which are in themselves inelastic constitute the rubbing surface of the massage device, and may be mounted in any suitable way on separate pins, as shown, or upon integral gudgeons, as illustrated in 95 5 certain rollers in Figs. 2 and 3 of the drawings and hereinafter more particularly described; the pins or gudgeons B being journaled to rotate in bearings formed in side plates C D formed on or carried by bar E, or arranged in any other suitable manner for rotation. 100

In practice it has been found efficient for the ends of the pins B to extend through and beyond the side plates, and carry rounded end pieces F, which also rotate with the pins B and rollers A. The rollers are shown in the form of short cylindrical sections, and 105 occupy the space between the side plates C D, being arranged in parallel relation with respect to each other, and spaced in juxtaposition at a proper distance apart. The rollers A, supported and arranged as above described, present a roller rubbing surface capable of being applied to the surface of the body at any desired point and with any proper degree of pressure, either 110

by securing the bar to any suitable object and moving the body back and forth against it, or by grasping the ends of the bar E and moving such bar back and forth endwise with the rollers bearing over and against the 5 surface of the body to be massaged. A brisk movement of the bar in the manner described results not only in developing friction, but the pounding due to the successive rollers coming in contact with the body, and the consequent vibrations thereby imparted, 10 quickly produces a combined rubbing and kneading effect upon the surface of the body at the point of application of the device, which is beneficial, and which effect cannot be so beneficially secured by purely hand manipulation. And by suitably shifting the bar 15 about, it will be readily seen that the device may be applied to any desired portion of the surface of the body, thereby securing in a most simple and efficient manner the beneficial effects of the massage.

It may sometimes be desirable to secure the device 20 in stationary position when required for use, and also to adjust its height so as to be brought into position for any desired part of the body to be rubbed against the roller rubbing surface of the device. In Figs. 1 to 5, I have shown a construction embodying this idea, 25 and in Fig. 1, I have shown the device as applied to a doorway as a convenient place of attachment. In this case I provide the bar E with adjustable clamping shoulders K L adapted to engage against the inside surface of the door jambs, while the ends of the bar E 30 rest or bear against the outer surfaces or faces of the jamb, as clearly indicated in Fig. 1. In order that the device may be readily applicable to any width of doorway, one of the clamping jaws or shoulders K L may be adjustably secured to the bar E. To this end, 35 I provide one end of bar E with a series of holes M therethrough, in any one of which may be received a bolt N, which is arranged to pass through an elongated slot O in jaw K. By this means an approximate adjustment of jaw K may be secured by inserting the 40 bolt N through the proper hole M in bar E, and then securing a more accurate adjustment by loosening up on nut P and shifting the jaw K, the slot O permitting such shifting movement of the said jaw. In order to securely clamp and hold the device in the doorway, the 45 jaw L may be made movable, and a lever Q, having a cam face R, arranged to bear against the rear edge of said jaw L. A spring S serves to yieldingly draw the jaw L into one limit of its movement, while by rocking lever Q the cam face thereof is brought into bearing 50 relation against the jaw L, and said jaw is forced outwardly, thereby securing a clamping effect against the door jamb.

In the manner above described, it is obvious that the 55 height of the device in the doorway may be readily and quickly adjusted. If desired, and in order to avoid injuring or marring the door jambs by the application of the device thereto, the engaging or bearing surfaces of the jaws K L, and also the surfaces of the bar E which bear against the door jamb, may be faced with 60 felt or other suitable material, as indicated at T.

While I have referred to the device as being applied in a doorway, it is obvious that it may be stationarily secured in any other convenient place.

In the foregoing description I have referred to the 65 rollers as being mounted on pins B, and which pins

are journaled to secure axial rotation of the rollers. I do not desire, however, to be restricted or limited to pins passing all the way through the rollers, as gudgeons or pintles may be employed to secure the same results, and in Figs. 2 and 3 I have illustrated this idea, 70 wherein the roller F' is shown as being turned down to form journal pintles or gudgeons G', on which the roller may rotate. In this form of roller, the end pieces H' are formed integrally with the roller. When, therefore, I speak of pins as forming the journals for the rollers, I desire to include broadly pintles or gudgeons. 75

From the foregoing description it will be seen that I provide an exceedingly simple, efficient and inexpensive massage device, which may be applied to any part of the body, and by which may be secured in a 80 most satisfactory degree the beneficial effects of massage.

In order that the invention might be fully understood by those skilled in the art, the details of the foregoing embodiments thereof have been thus specifically described, but 85

What I claim as new and desire to secure by Letters Patent is:—

1. In a massage device, a frame having side pieces, said side pieces having journal bearings formed therein, in combination with a plurality of rollers extending in parallel relation to each other from one side piece to the other to form a roller rubbing surface, and having journals intermediate their ends mounted in the bearings formed in said side pieces the periphery of said rollers projecting beyond the edge of the frame on each side of the journals. 90
2. In a massage device, a frame having side pieces arranged in parallel relation a plurality of rollers journaled in said side pieces and arranged in juxtaposition to form a roller bearing surface, each roller having rounded end pieces associated therewith. 100
3. In a massage device, plurality of inelastic rollers arranged in parallel relation with respect to each other to form a roller bearing surface, each roller being provided with straight ends and having rounded end pieces associated with each end thereof. 105
4. In a massage device, a frame having side pieces arranged in parallel relation to each other a plurality of rollers, pins on which said rollers are mounted, journal bearings formed in said side pieces and in which the ends of said pins are mounted to rotate, the ends of the pins extending beyond the journal bearings, and end pieces mounted on the projecting ends of the pins. 110
5. In a massage device, a rigid bar having parallel side pieces, pins having their ends respectively extending through said side pieces and arranged parallel to each other, a non-yielding roller carried by each pin and extending from one side piece to the other, and end pieces carried by the projecting ends of said pins and outside of said side pieces. 115
6. In a massage device, a bar having side plates, transversely extending pins journaled in said side plates and having their ends projecting beyond said side plates, rollers mounted on said pins between the side plates, and rounded end pieces carried by the projecting ends of the pins. 120
7. In a massage device, a bar, in combination with inelastic rollers journaled on one side thereof and arranged to form a roller rubbing surface, and rounded end pieces connected to the ends of said rollers on each side of the bar. 125
8. In a massage device, a bar, rollers journaled thereon and arranged to form a roller rubbing surface, and means for stationarily clamping said bar at any desired height in a doorway. 130
9. In a massage device, a bar, rollers journaled thereon and arranged to form a roller rubbing surface, and clamp jaws carried by said bar whereby said bar may be stationarily clamped at any desired height in a doorway. 135
10. In a massage device, a bar, rollers journaled thereon and arranged to form a roller rubbing surface, and clamp jaws adjustably mounted on said bar whereby said bar 140

may be stationarily clamped at any desired height in a doorway.

11. In a massage device, a bar, rollers journaled thereon and arranged to form a roller rubbing surface, a clamp jaw 5 adjustably mounted on said bar at one end thereof, a coöperating clamp jaw movably mounted on said bar at the other end thereof, means for yieldingly maintaining said movable jaw in retracted position, and a cam lever pivotally mounted on said bar and arranged to engage said jaw 10 to actuate the same into clamping position.

12. In a massage device, a bar, side plates thereon, pins journaled in said side plates, rollers carried by said pins and arranged to form a roller rubbing surface, a series of holes formed through said bar at one end thereof, a slotted 15 clamp jaw, a securing bolt adapted to pass through the slot

in said clamp jaw and any one of the holes through said bar, a coöperating movable clamp jaw carried by the other end of said bar, and a cam lever for operating said movable clamp jaw.

13. In a massage device, a bar having an undulated face, 20 a clamp jaw adjustably mounted on said bar at one thereof, a coöperating clamp jaw movably mounted on the other end of said bar, and a rubbing surface carried by said bar.

In witness whereof, I have hereunto set my hand this 26th day of August 1904, in the presence of the subscribing 25 witnesses.

SYLVANUS F. BOWSER.
